UNITED STATES PATENT OFFICE.

HARRY E. MEYER, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed July 15, 1920, Serial No. 396,537. Renewed November 6, 1925.

My invention relates to control apparatus and it has special relation to attachments for controllers of the well-known "K" type for electric railway vehicles.

5 The object of my invention is to provide an automatic release for an auxiliary controller whereby it is impossible for the motors of a car to operate after the motorman has removed his hand from the controller 10 handle.

This device is intended to prevent careless 15 operation of the car and to decrease the chances for an accident should the motorman become unable to continue his duties while the car is in operation.

More specifically stated, the object of my 20 invention is to provide a protective device for an auxiliary controller similar to the one which has been fully described in the application for a patent of L. G. Riley, et al., 25 Serial Number 381,980, filed May 17, 1920, and assigned to the Westinghouse Electric & Manufacturing Company. The invention consists in so positioning springs between 30 the relatively movable parts of the auxiliary controller that the parts must assume a predetermined angular relation when the motorman releases the controller handle, thereby preventing the line switch from remaining closed.

For a better understanding of my invention, reference may be made to the accompanying drawings, wherein

Fig. 1 is a view, in side elevation, of an 35 auxiliary controller embodying my invention, installed upon a "K" controller.

Fig. 2 is a transverse sectional view, taken along the line II—II of Fig. 3.

Fig. 3 is a longitudinal, sectional view, 40 taken along the line III—III of Fig. 2.

Fig. 4 is an elevational view of the interior parts of a switching attachment which is automatically released by springs in accordance with my invention, the casing member being shown in section.

Figs. 5 and 6 are transverse, sectional views, taken along the line V—V of Fig. 2, and show the dogs and springs in an operative position and in an inoperative position, respectively.

Fig. 7 is a diagrammatic view of a portion of a motor-control system which serves to indicate the proper circuit arrangement and operating sequence of the contact members embodied in my switching attachment.

Fig. 8 is a cross sectional view of the lower dog member taken along the line VIII—VIII of Fig. 6.

Referring to Fig. 1 of the drawings, an auxiliary controller 1 comprises a casing 2, a side cover 3 that is secured thereto by tap screws 4, a controller handle 5, a position-indicating member 6 and a stop member or curved lug 7. The auxiliary controller is mounted upon a main controller 8 of the well-known "K" type having a reverse switch handle 9 to the left of the auxiliary controller.

In Figs. 2, 3 and 4, the casing 2 and the side cover 3 of the auxiliary controller 1 are shown in cross-section. The position-indicating member 6 is mounted upon a short shaft member 10, being secured thereto by a pin 11. The controller handle 5 is mounted upon the shaft 10 above the position-indicating member 6, as is shown in Fig. 1. The shaft 10 projects through a water cap or boss 13, which is part of the casing 2. An upper dog or cylindrical casting 12 is mounted upon the lower portion of the shaft 10, positioned thereon by means of a nut or tap collar 14. A pin 15 prevents the collar 14 from rotating.

A second or lower dog member or cylindrical casting 16 is fitted over the customary drum shaft 17, which extends through the controller cover 18 and a water cap or boss 19. The water cap or boss 13 and the boss 19 are provided with bearings 20 and 21, for the shaft 10 and for the shaft 17, respectively.

An indicating disk 22 is mounted upon the top of the casing 2 and a pointer or toe 23, forming part of the position-indicating member 6, indicates to the operator the position that is occupied by the controller drum at all times.

The upper dog member 12 is provided with lugs or projecting portions 24 having recesses 25. An annular drum 26 of insulating material, such, for example, as a molded composition formed of fibrous material and a binder, is mounted upon the dog 12 by means of screws 27 which are positioned in the holes or recesses 25. A sealing compound 28 is disposed in the outer portion of the holes 25, to secure adequate insulation. A contact strip or segment 29 is mounted upon the annular drum 26 by means of suitable tap screws (not shown).

The lower face of the dog 12 has downwardly projecting curved blocks or lugs 30 and 31 which are oppositely disposed the one to the other, as shown in Figs. 2, 5 and 6.

The lower dog 16 comprises radially extending arms or lugs 32 on which is mounted an annular drum 33, similar in construction to the insulating drum 26. The drum 33 is secured to the lugs 32 by screws 34, which are covered with suitable insulating material 35. A contact strip or segment 36 is mounted upon the annular drum 33 by means of suitable tap screws (not shown).

The upper surface of the dog 16 is provided with two upwardly projecting lugs 36a and 37 which are oppositely disposed the one to the other. These lugs occupy different positions in the same general plane and correspond to the interlocking blocks 30 and 31, being thus adapted to interlace with them.

The angular space between confronting blocks is probably about 35° , that is, the upper dog 12 has 35° of free travel before striking the lower dog 16 in the one or the other direction. It should be noted that the various structural figures, with the exception of Fig. 5, illustrate my device as occupying its "Off" position, corresponding to the forward movement of 35° by the upper dog 12.

A relatively deep recess is drilled in the upper side of the curved block 36a and a pin 38, having a conical head projecting slightly above the upper face of the block 36a, is resiliently mounted therein by means of a spring 38a (see Figs. 2 and 8). A corresponding recess 39 is drilled in the lower face of the dog 12 between the curved blocks 30 and 31 and the upwardly projecting pin 38 is adapted to engage the recess when the blocks are in the position shown in Fig. 5. The purpose of the pin 38 is to prevent the contact surfaces of the curved blocks 30 and 36a from disengaging because of the unavoidable jarring of the vehicle or slight relaxation of pressure upon the handle 5 by the operator.

A plurality of recesses 40, 41, 42 and 43 are provided in the curved blocks 30, 31, 36a and 37, respectively, in the manner best shown in Figs. 5 and 6. A helical spring 44 is positioned in the recesses 40 and 42 of the curved blocks 30 and 36a and a similar spring 45 is in like manner positioned in the recesses 41 and 43 of the curved blocks 31 and 37, respectively.

Fig. 6 shows the curved blocks 30, 31, 36a and 37 in the "Off" position. The springs 44 and 45 tend to maintain the blocks in this relative angular position.

In Fig. 5, the curved blocks 30, 31, 36a and 37 are shown in the only relative position that will secure the completion of the electrical circuit hereinafter described. It is apparent that in this position the helical

springs 44 and 45 are in compression and as soon as the operator of the car removes his hand from the handle 5 the springs 44 and 45 will so separate the contact faces as to assume the relative position shown in Fig. 6.

Fig. 4 shows a contact finger 46 which is provided with a suitable contact tip 47 that is secured to the lower face of the annular drum 26 and is electrically connected to the contact strip 29. The contact tip 47 engages a contact strip or block 48, which is secured to the upper face of the annular drum 33, only when the curved blocks 30 and 36a are in contact with each other, as shown in Fig. 5, and a relatively small angular movement of the blocks removes the contact tip 47 from the block 48.

The contact strip 48 is electrically connected to the contact segment 36. The lower face of the annular drum 26 has an insulating channel member 49 secured thereto to prevent the contact member 46 from coming in contact with any other portions of the dog 16. A similar channel member 50 protects the portion of the annular drum member 33 which is adjacent to the contact block 48.

A relatively short contact plate or segment 51 is mounted upon the periphery of the drum 33 and is electrically connected to the contact strip 36. A plurality of contact fingers 52, 53 and 54 are mounted upon a finger-board 54a and are adapted to engage the contact segments 29 and 36 and the contact strip 51, respectively, during predetermined periods of the drum rotation. Suitable electrical terminals 55 are provided for the contact fingers 52, 53 and 54.

Fig. 2 shows the method of mounting the finger-board 54 upon a projection 56 of the casing 2 by means of a plurality of bolts 57.

The operation of my invention and the electrical circuits established thereby will now be described:

In Fig. 7, the system shown comprises various contacting members of my auxiliary switching attachment and a portion of those to be found in the "K" controller or main switching device 8. In addition, supply-circuit conductors respectively marked "Trolley" and "Ground", a line switch "LS" and a main-motor-circuit or accelerating resistor 58 are shown.

Under normal conditions, that is, when the controller handle has been moved to its extreme position, corresponding to the right-hand vertical face of the stop member 7 (Fig. 1), the electrical circuits are arranged as in Fig. 7, wherein it will be seen that this "normal" position lies a certain distance beyond the line corresponding to the familiar "off" position of drum controllers. In this particular case, I prefer an angular distance of approximately 35° between the "normal" and "off" position that corresponds to

ward or advanced drum movement, as previously set forth. At this time, the controller finger 52 engages one portion of the upper contact segment 29, while the controller finger 53 is in an intermediate position between the ends of the contact segment 36. Consequently, no circuit is completed, although a live circuit extends as far as the tip of the control finger 46 between the rotatable auxiliary drum members 12 and 16. The curved blocks or tongues 30, 31, 36a and 37 and the helical springs 44 and 45 are in the position shown in Fig. 6. It is apparent that the springs 44 and 45 are under relatively slight pressure in this position.

Under these conditions, the interlocking tongues upon the confronting end faces of the rotatable dogs 12 and 16 are separated by the above-mentioned angular distance of 35° in a direction to be considered as forward, namely, clockwise when viewing the auxiliary controller apparatus from the top, as indicated by the arrow in Fig. 2. This condition of the interlocking dogs is shown in Fig. 7.

Upon forward movement of the auxiliary shaft 10 by the controller handle 5 for a distance of 35° the customary "Off" position of the "K" controller 8 is reached. Such movement of the auxiliary shaft 10 has effected the rotation of the upper dog 12 alone, and has compressed the helical springs 44 and 45 in the manner shown in Fig. 5 of the drawings. In this position, the curved blocks 30 and 31, respectively, engage the curved blocks 36a and 37, and the contact tip 47 of the control finger 46, which is located between the dogs 12 and 16, engages the contact block 48. In this way the energization of the auxiliary switching attachment extends as far as the contact segments 36 and 51 and, in fact, through control finger 53 and conductor 75 to auxiliary contact finger 76 of the line switch LS.

Consequently, at this time, the two dogs 12 and 16 are mechanically interlocked as shown in Figs. 2, 3, 4 and 5, respectively, and continued movement of the controller handle 5 in the forward direction of the auxiliary shaft 10 will effect simultaneous travel of the contact segments 29 and 36 and of the main controller shaft 17.

As soon as the "Off" position is reached, a further mechanical action takes place in the nature of the insertion of the pin 38, which is associated with the lower dog 16, into the recess 39 in the confronting end face of the upper dog 12. While this lock is only temporary and may be removed by the backward action of the controller handle it, nevertheless, serves a useful purpose in preventing the two dogs from becoming accidentally separated by reason of jars caused by the operation of the controller or by the travel of the vehicle. It is to be understood that

this pin does not exert sufficient pressure in this position to prevent the separation of the contact blocks 30 and 31 from the contact blocks 36a and 37 by the springs 44 and 45 if the operator releases the handle. Thus, when once the upper dog 12 has been actuated to the "Off" position, corresponding to the electrical connection of the upper and the lower contact segments 29 and 36, such connection is maintained throughout the forward operation of the control apparatus, though there be slight inequalities of pressure upon the handle 5 by the operator.

Movement of the control apparatus of approximately 46° from the "Off" position to the "Run" position, which corresponds to the initial operative position of the "K" controller, first causes the contact segments 61 of the "K" controller to engage with the control fingers 62 and 63. In this way, a circuit is established from one stationary contact terminal 64 of the line switch "LS" through conductor 65, control fingers 62 and 63, which are bridged by contact segment 61 of the "K" controller, and thence through accelerating resistor 58 and the vehicle motor or motors to Ground. Consequently, the initial circuit through the "K" controller is completed before the line switch LS is closed, whereby it is insured that the arcing incident to the completion of the main motor circuit will be taken by the line switch LS.

Such circuit completion is effected as soon as the control apparatus reaches the above-mentioned "Run" position, wherein the contact strip or segment 51 of the auxiliary switching attachment engages the control finger 54. Under these conditions, a circuit is established from the trolley through conductor 66, auxiliary-circuit hand switch 67, conductor 68, control finger 52, contact segment 29, control finger 46, contact block 48, contact segments 36 and 51 and control finger 54 of the auxiliary switching device, whence circuit is continued through conductor 69, a suitable resistor 70 and the actuating coil of the line switch LS to Ground.

The consequent closure of the line switch LS completes a main circuit from the trolley through conductor 71, main hand switch 72, and conductor 73, and contact disk 74 of the line switch LS to stationary contact terminal 64, whence circuit is completed through the "K" controller, as already traced.

As soon as the line switch LS is closed, a holding circuit therefor is formed from the contact segment 36 on the lower dog 16 through control finger 53, conductor 75, stationary contact terminal 76, auxiliary disk or contact block 77 of the line switch, whence circuit is continued through terminal 57 and conductor 56 to the controller finger 54. Consequently, the continued energization of the actuating coil of the line switch is insured, even though the contact segment 51

becomes disengaged from the control finger 54 after the controller leaves its initial operative or "Run" position.

However, although the closure of the line switch is thus maintained, the provision of a lifting circuit for the line switch in the first operative position only of the controller is desirable. Whenever the line switch has been opened, during motor operation, by the 10 backward movement of the controller, as about to be described, the line switch LS should not again be closed until the controller has been returned to its initial operative "Run" position. In this way, it insures that the entire accelerating resistor 58 will be connected in circuit with the vehicle motor or motors before the connection to the supply circuit is effected.

Continued movement of the controller 20 handle in the forward direction operates the entire apparatus as a unit, as previously mentioned, to effect any desired manipulation of the main control circuits, such as the successive short-circuit of sections of the 25 accelerating resistor 58. Since this operation is well known in the art and, furthermore, since the particular type of system is not material to my present invention, I do not deem it necessary to further illustrate or 30 describe the main circuits.

When it is desired to shut off the power, the controller handle is actuated in the reverse direction and finally strikes the right-hand vertical face of the stop member 7. 35 The first actions accomplished by such backward movement of the controller handle are the enforced depression of the pin 38 and the reverse travel of the upper dog 12 for an angle of 35°. The dog 12 is actuated 40 rearwardly until the opposite end faces of the interlocking blocks 30 and 31 come in contact with the confronting end faces of the interlocking blocks 36a and 37 on the lower dog 16. This distance is again preferably 35°, in which event the intermediate 45 control finger 46 occupies a position relative to the lower contact segment 36, as indicated in Fig. 7 by the legend "Off" position, returning.

Consequently, the initial backward movement of the controller handle interrupts the circuit between the contact finger 46 and the contact block 48 thereby de-energizing the actuating coil for the line switch LS, which 55 immediately opens and thus takes all the arcing that is caused by such interruption of the main-motor circuit.

The resilient springs 44 and 45 are sufficiently powerful to cause the dog 12 to assume an angular position with relation to the dog 16 similar to that shown in Fig. 6 if the operator should, for any reason, remove his hand from the controller handle when the power is on. In this way, the

opening of the line switch LS occurs to de- 65 energize the motors.

After the line switch LS has thus been opened, the lower dog 16 and the "K" controller 8 may be backwardly rotated by hand as a unit with the upper dog 12 until the 70 extreme position marked "Normal" is again reached, when all of the parts occupy the positions illustrated in Fig. 7. It is apparent that embodying this automatic release in the auxiliary controller does not 75 change other desirable features thereof, such as the closing of the main line switch after the main controller is in the "Run" position and the opening of the main line switch before the main control circuit is 80 broken, thereby preventing arcing and burning of the controller segments and fingers during both forward and backward movements of the controller.

While I have shown my invention in its 85 preferred form, it will be obvious to those skilled in the art that it is not so limited but is susceptible of various alterations and changes without departing from the spirit thereof. I desire, therefore, that only such 90 limitations shall be placed thereupon as are imposed by the prior art or as are specifically set forth in the appended claims.

I claim as my invention:

1. The combination with a plurality of 95 relatively movable contact-carrying devices arranged in axial alinement and means for mechanically interlocking said devices only after one of said devices has been actuated through a predetermined distance, of inter- 100 dependent resilient means for biasing said devices in predetermined relation.

2. The combination with a control-drum 105 shaft, of an auxiliary contact-carrying device attached to said shaft, a second shaft adapted for manual operation, a second contact-carrying device mounted on said second shaft and having a mechanically interlocking 110 relation to the first-named device to effect the actuation of the control-drum shaft upon the operation of said second shaft and a compression spring interposed between 115 said devices for maintaining them in predetermined relation to each other during discontinuance of such manual operation.

3. The combination with a control-drum 120 shaft, of an auxiliary contact-carrying device attached to said shaft and having a rigid projection, a second shaft adapted for manual operation, a second contact-carrying device mounted on said second shaft and having a rigid projection adapted to engage 125 the first-named projection to effect direct interlocking of said devices during a certain range of travel, and resilient means tending to maintain said projections in predetermined angular relation to each other.

4. The combination with a control-drum

shaft, of an auxiliary contact-carrying device attached to said shaft and having a projection provided with a recess, a second shaft adapted for manual operation, a second contact-carrying device mounted on said second shaft and having a projection adapted to engage the first-named projection during a certain range of travel, said projection of said second contact-carrying device being provided with a recess, and a resilient member extending between said projections and positioned in said recesses.

5. The combination with a control-drum shaft, of an auxiliary contact-carrying device attached to said shaft, and having a plurality of lugs of angular dimensions corresponding to a predetermined position of the travel of the device, a second shaft adapted for manual operation, a second contact-carrying device mounted on said shaft and having a projection located between the first-named projections to selectively engage them after a predetermined degree of travel in the one or the other direction, and means 25 for actuating said second contact-carrying device to an electrically inoperative position upon cessation of said manual operation during the occupation of a running position by said first device.

30 6. Control apparatus comprising a plurality of rotatable members, one of which is actuated by the other, a contact device disposed between said members and electrically connecting them, and automatic means for preventing said contact device from remaining in a closed position by effecting relative angular movement of said members.

35 7. Control apparatus comprising a plu-

rality of manually operated relatively rotatable contact members, co-operating contact devices mounted upon each of said members, and means for so rotating one of said members that said contact device must assume an open position when said manual operation ceases.

40 8. Control apparatus comprising a plurality of aligned rotatable members, a contact device adapted to effect connection between the confronting end surfaces of said members, and a resilient member positioned between said rotatable members for yieldingly maintaining said rotatable members in predetermined angular relation.

45 9. The combination with a control-drum shaft, of an auxiliary contact-carrying device attached to said shaft, a second shaft adapted for manual operation, a second contact-carrying device mounted on said second shaft, means for mechanically interlocking said device, a contacting device located between said contact-carrying devices for effecting connection between the confronting end surfaces thereof, and means tending to 50 interrupt said connection.

55 10. The combination with a main controller and a line switch, of an auxiliary manually operated controller for closing and opening said line switch and for actuating said main controller and means within said auxiliary controller for effecting the opening of said line switch if manual operation 60 stops.

65 In testimony whereof, I have hereunto subscribed my name this 10th day of July 1920.

HARRY R. MEYER.
